UNITED STATES PATENT OFFICE

168,503

FLOWER PLANTER

Paul G. Hallas, Grand Rapids, Mich.

Application June 25, 1952, Serial No. 20,349

Term of patent 7 years

(Cl. D35—3)

To all whom it may concern:

Be it known that I, Paul G. Hallas, a citizen of the United States, residing at Grand Rapids, in the county of Kent and State of Michigan, have invented a new, original, and ornamental Design for Flower Planters, of which the following is a specification, reference being had to the accompanying drawing, forming part thereof.

In the drawing:

Fig. 1 is a perspective view of the flower planter, showing my new design;

Fig. 2 is a top plan view; and

Fig. 3 is a bottom plan view.

I claim:

The ornamental design for a flower planter, as shown.

PAUL G. HALLAS.
